(57)

CLAIM

The ornamental design for a ring, as shown and described.

DESCRIPTION

FIG. 1 is a top front left side perspective view of a ring; FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

In the drawings, the broken lines represent portions of the ring which form no part of the claimed design.
